UNITED STATES PATENT OFFICE.

FRANK J. FITZPATRICK, OF FREDERICK, MARYLAND.

CORN-HUSKING MACHINE.

SPECIFICATION forming part of Letters Patent No. 722,448, dated March 10, 1903.

Application filed February 2, 1901. Serial No. 45,708. (No model.)

To all whom it may concern:

Be it known that I, FRANK J. FITZPATRICK, a citizen of the United States of America, residing at Frederick, in the county of Frederick 5 and State of Maryland, have invented certain new and useful Improvements in Corn-Husking Machines, of which the following is a specification.

This invention relates to corn-husking machines, and more particularly to that class which not only husk the corn, but are adapted to remove the silk as well.

The object of this invention is to provide a machine for removing the husk and silk 10 from corn, one in which the corn is fed into a hopper and is carried on a series of belts throughout the entire process, in which both ends of the ear are removed, the husk and silk taken off, and the corn deposited in a 15 suitable receptacle at the end of the machine.

With these objects in view and such others as may hereinafter appear my invention consists in the particular construction of the various parts and in the novel manner of combination and arrangement of said parts, all 20 of which will be more fully described, and specifically pointed out in the appended claims, which are intended to accord in their terms, spirit, and meaning with the prior 25 state of the art and the existing law.

In the drawings forming a part of this specification, Figure 1 is a side elevation of the complete machine. Fig. 2 is a top plan view. Fig. 3 is a sectional view taken on line $\alpha\alpha$, Fig. 1. Fig. 4 is an enlarged detail view. Fig. 5 is an enlarged detail view. Fig. 6 is 30 a plan view of the silk-removing device. Fig. 7 is a top plan view of the elongated cam.

Referring by numerals to the drawings, 1 35 represents the table or frame supporting the mechanism, having secured to one end thereof a hopper 2, into which the corn is fed. Journaled in suitable bearings at each end of this table are shafts 3 and 4, each carrying oppositely-disposed sprockets 5 and 6, connected by sprocket-chains 7 and 8, having mounted thereupon oppositely-disposed U-shaped supports 9, adapted to receive the ears of corn.

40 The shaft 3 is provided with a circular

knife 10 and is adapted to be driven by a pulley 11, connected to an engine by the belt 12. The pulley 11 is also connected by the belt 13 to the pulley 14, mounted on the shaft 15, carrying the circular knife 16. 55

Mounted in suitable brackets or supports over the shaft 4 is a shaft 17, carrying a series of oppositely-disposed blades or knives 18, adapted to split the husk upon the ear, and a gear 19, which meshes with a corresponding gear 20, keyed to the shaft 4. Meshing with a gear 20', keyed to the end of shaft 4, is a gear 21, which is keyed upon and adapted to drive the shaft 22, carrying sprockets 23, which are connected by sprocket-chains 60 24 and 25 to corresponding sprockets 26, mounted upon the shaft 27 at the rear end of the table.

Mounted upon the sprocket-chains 24 and 25 are revolving spring-actuated plungers 28, 70 having upon their inner ends a series of prongs 29 for engaging the ends of the ears and provided upon their outer ends with cogged stops 30, adapted to engage elongated cams 31, which are secured upon the top of 75 the table and curve around the end. The curved ends of these cams extend beneath the table and are sufficiently close together to engage the inner sides of the stops 30 when in the position shown in Fig. 5, their curved 80 portions diverging, so as to gradually force the stops apart as they travel along the cams, as shown in Fig. 4, in which position the spring-actuated plungers 28 are depressed. The stops, and thus the spring-actuated plungers 85 28, carrying the prongs 29, retain the position shown in Fig. 4 until they are brought in a line with an ear of corn held in the U-shaped supports, at which point the parallel portions of the elongated cams 31 end, there- 90 by releasing the stops and permitting the plungers 28 to spring inward with sufficient force to drive the prongs 29 into the ends of an ear of corn and to hold the same so firmly that it will be easily taken from the U-shaped 95 support. The ear is then carried over the rotary brushes by the prongs upon the spring-actuated plungers, which are caused to revolve by the cogs upon the stops engaging the cogged bar 31', arranged beneath the table. 100

The plungers are forced apart, and thus the prongs drawn from the ear, and accordingly the ear is dropped, when the stops are brought in contact with the curved portions of the 5 cams upon repeating the action just described.

Meshing with the gear 21 is a gear 32, keyed upon and adapted to drive the shaft 33, carrying beveled gears 34, which mesh with beveled gears 35, keyed to shafts 36, supporting 10 rotary brushes 37. The gear 32 meshes with a gear 38, having a bevel-gear face 39 meshing with a beveled gear 40, keyed upon and adapted to drive the shaft 41, having a series of beveled gears 42 engaging beveled 15 gears 43, which are keyed upon the shafts 44, having a series of fingers 45, arranged in rows thereupon for picking the silk from the brushes.

Mode of operation: The corn is fed into the 20 hopper. From there it is received by the U-shaped supports and brought in contact with the circular knife 10, then in contact with the circular knife 16, thereby removing both ends, after which it passes under and is 25 brought in contact with one of the blades 18 of the rotary knife, and from thence it passes on until the U-shaped support is brought in a line with the spring-actuated pistons, at which point the elongated cams release the 30 spring-actuated pistons and permit the prongs thereupon to engage each end of the ear and to support the same while it is passed over the rotary brushes, after which it is released at the end of the table, where the stops upon 35 the spring-actuated pistons engage the elongated cams.

From the foregoing description and the accompanying drawings the construction, operation, and advantages of the invention will 40 readily be seen, and I desire it to be understood that I do not limit myself to the precise details of construction herein shown and described, as I may without departing from the

spirit of the invention make various minor changes therein.

45

Having thus described the various features of my invention, what I claim as new, and desire to secure by Letters Patent, is—

1. In a corn-husking machine a table provided with two shafts having sprockets 50 mounted thereupon, of sprocket-chains connecting the said sprockets, the said sprocket-chains carrying revolving spring-actuated pistons having prongs upon one end and stops upon the other, of elongated cams for 55 governing the pistons, of a series of rotary brushes arranged beneath the table and a series of brush-cleaners working in connection with the said rotary brushes, substantially as shown and described.

2. In a corn-husking machine, a frame or table having a hopper at one end thereof, of shafts journaled upon the said table the said shafts carrying sprocket-gears connected by sprocket-chains having a series of oppositely- 65 disposed U-shaped supports, of circular knives mounted upon shafts on opposite sides of the said sprocket-chains, of a rotary knife driven by a set of gears, of a second set of shafts carrying sprocket-gears connected by 70 sprocket-chains provided with a series of revolving spring-actuated plungers having prongs upon one end and a stop upon the other, of cams upon the table for engaging the stops upon the plungers, of a series of rotary brushes and a series of brush-cleaners working in connection with the said brushes, substantially as shown and for the purpose set forth.

In testimony whereof I hereto set my hand 80 in the presence of two witnesses.

FRANK J. FITZPATRICK.
